UNITED STATES PATENT OFFICE

147,165

DESIGN FOR A CIGARETTE AND MATCH
HOLDER

John D. Tuomey, Forest Hills, N. Y., assignor to Union Aircraft Products Corporation, New York, N. Y., a corporation of New Jersey

Application April 27, 1946, Serial No. 129,060

Term of patent 3½ years

(Cl. D85—2)

To all whom it may concern:

Be it known that I, John D. Tuomey, a citizen of the United States, residing at Forest Hills, in the county of Queens and State of New York, have invented a new, original, and ornamental Design for a Cigarette and Match Holder, of which the following is a specification, reference being had to the accompanying drawing, forming a part thereof.

I claim:

The ornamental design for a cigarette and match holder, as shown.

JOHN D. TUOMEY.
